UNITED STATES PATENT OFFICE.

LANIUS J. RUTHERFORD, OF NATCHEZ, MISSISSIPPI.

GATE LATCH.

Application filed November 15, 1921. Serial No. 515,336.

To all whom it may concern:

Be it known that I, LANIUS J. RUTHERFORD, citizen of the United States, residing at Natchez, in the county of Adams and 5 State of Mississippi, have invented new and useful Improvements in Gate Latches, of which the following is a specification.

This invention relates to a gate latch, and the object is to provide for securing a gate 10 at the usual point, and at a point near the bottom, the two securing devices having a particular relation, and being operable at the same time.

A further object is to provide a construction which shall include a pivoted securing device so designed and mounted that it will impart vertical movement to a bar having an offset at its lower end,—the offset portion engaging a socket in one of the uprights 20 of the gate, whereby both securing devices are retained in locking position.

A still further object is to provide, in connection with the foregoing construction, a pivoted latch movable on an axis parallel 25 with the closed gate, and entering a socket in the gate post, the latch carrying an arm by means of which the lower gate securing element is controlled.

With the foregoing and other objects in 30 view, the invention consists in the novel construction and arrangement of elements described and claimed, it being understood that modifications may be made within the scope of the claims without departing from 35 the spirit of the invention.

In the drawings, Figure 1 is an elevation of the gate and the mounting and fastening devices; Figure 2 is an elevation of that portion of the fastening means secured to the 40 face of the gate post; Figure 3 is a transverse section on line 3—3 of Figure 1; Figure 4 is a section on line 4—4 of Figure 1; Figure 5 shows the engaging devices carried by an element of the gate; Figures 6 45 and 7 illustrate details of construction described below.

The gate 10 includes an upright 12, which, when the gate is closed, is adjacent to the gate post 14. This gate post is provided 50 with a main recess 15, receiving the U portion 16 of a plate 17, the outer portions of the plate or strip being mortised in the front of the post and suitably secured.

Formed on the plate 17, or welded thereon, are ears 18, 19, receiving a pin 20 which serves to pivotally mount the latch 21, the

latter being curved as shown and the end 22 entering the U portion 16.

An arm 23 extending from the latch is engaged by the hooked end 24 of the vertical 60 rod 25, this rod extending through channel 26 of the post and having an offset end 27 projecting through a slotted plate 28 mounted on the surface of the post adjacent the gate when the latter is closed. 65

The upright 12 of the gate is provided with a socket 30 near its lower end, the entrance portion of the socket being designated 31. This socket receives a strip 32 including a U portion disposed within the 70 socket per se, and also including an outwardly and downwardly extending portion 33. When the gate is closed, the offset 27 rides up on the inclined portion and lifts the rod 25, swinging the latch 21 by means 75 of the arm 23.

At the same time, a pin 34, carried by element 12 of the gate, engages the outer portion of the curved surface of the latch, and this action also tends to swing the latch 80 toward the central portion of the U member 16, permitting the pin to pass inwardly to a position where it is free of the latch, and the latter moves by gravity to locking position. The vertical rod and its offset end 85 move downwardly at the same time, and the offset enters the socket provided therefor, so that the gate is secured at two points.

By pressing the outer portion of latch 21 with the fingers, the pin 34 is freed and 90 the offset member 27 is raised to a position where it will release the gate. If either portion of the device tends to stick slightly because of weather conditions, the locking operation will be facilitated because of the 95 double arrangement described.

What I claim is—

1. In a device of the class described, a plate including a U portion for reception within a socket of a gate post, a device to 100 be carried by a vertical member of a gate and positioned to enter the U portion when the gate is closed, a latch pivoted on the outer portion of the plate and having a curved end entering the U portion, the latch 105 being movable to permit said device on the gate to pass beyond the latch into the U portion, and means for securing the latch in position to prevent said device from moving in the opposite direction. 110

2. In a device of the class described, a latch and means for pivoting the same on

a gate post, said post being provided with a socket and the free end of the latch being movable into the socket, a pin to be mounted on a vertical element of a gate in position 5 for moving into the socket upon engagement with the pivoted latch, the latch closing the socket upon the continued movement of the pin beyond the latch, an operating and retaining member pivoted to the latch, 10 and a socket formed in said element of the gate for receiving the retaining member and holding the latch inoperative.

3. In a device of the class described, a latch and means for pivoting the latch on a 15 gate post, the post being provided with a recess, and the free end of the latch being curved and movable into the recess, a pin to be mounted on a vertical element of a gate in position for entering the recess 20 upon engaging and passing the free end of the pivoted latch, an arm carried by the latch, a rod pivoted thereto, a device offset from one end of the rod, and a device to be car-

ried by said element of the gate and including a socket portion for receiving the 25 offset end and an inclined operating surface for engagement by the offset portion when the gate is closed, for elevating the rod, the socket permitting the rod to drop into position for retaining the latch inoperative. 30

4. The combination with a gate and gate post, the latter having a recess therein, of a plate including a U portion extending into the recess, a latch pivoted on an axis parallel with the gate when closed, the latch 35 having a lower free end projecting into the recess, a pin carried by the gate and entering the recess upon passing from the outer to the inner side of the latch as the latter moves about its axis, a vertically operative 40 element movable with the latch, and an inclined and socketed member carried by the gate for controlling the movement of the vertical member.

In testimony whereof I affix my signature. 45
LANIUS J. RUTHERFORD.
